OSCILLOGRAPH

Gerald M. Rassweiler and Edward J. Martin, Detroit, Mich., assignors, by mesne assignments, to General Motors Corporation, Detroit, Mich., a corporation of Delaware

Application January 14, 1931, Serial No. 508,666

5 Claims. (Cl. 171—95)

This invention relates to an oscillograph. It involves certain improvements over prior instruments of its kind, which improvements are designed to better the operation and to add to its range of usefulness especially when used with an engine indicator of a known kind, and having characteristics resembling those of the electric telemetric device shown in the patent to Peters, 1,528,627, March 3, 1925.

Among the objects sought to be attained by the present invention are an improved adjustable mounting for the source of light with relation to the instrument proper.

An improved drive for the rotating mirror used with instruments of this kind.

An improved shutter combined with a slit for the passage of the light beam, and mechanism associated therewith to adjustably determine the effective dimension of the slit, together with magnetically operated mechanism to open the shutter.

A combined viewing screen and film holder whereby the light diagram may be observed or photographed by merely sliding the combined unit.

An arrangement for definitely locating on the light diagram points corresponding to top and bottom dead centers of the engine piston, or other predetermined points as desired.

An arrangement for locating on the light diagram a point corresponding with the instant of ignition.

The instrument affords the opportunity of combining several related and associated accessory instruments on a single panel, preferably one of the side panels of the oscillograph, this panel being then a base for mounting such instruments as the engine indicator bridge, meters, resistance coils, and switches.

The above and other associated objects are accomplished by the structure constituting the improved device shown in the accompanying drawings and described below.

In the drawings—

Fig. 1 is a diagrammatic view.

Fig. 2 is a vertical longitudinal section.

Fig. 3 is a horizontal section, parts being shown in elevation.

Fig. 4 is a vertical section on line 4—4 of Fig. 2.

Fig. 5 is a side elevation of the shutter assembly.

Fig. 6 is a perspective of the shutter assembly.

Fig. 7 is a side elevation of a detail, the cylindrical lens.

Fig. 8 is a side elevation of a part of the vertical light shield.

Fig. 9 is a diagrammatic view showing the association of a transformer with the galvanometer coil.

Referring by reference characters to Fig. 1 of the drawings, A is a box-like housing. Light from a source B passes through a lens C, a shutter D, and is reflected from an oscillating reflector E constituting a part of the galvanometer. 10 The beam then passes through a cylindrical lens F and is reflected from a face of a revolving mirror G. The reflected beam is then received either on a viewing screen H, or on a film within a film holder I. It will be understood that if the 15 mirror G is revolved and if the galvanometer reflector is not oscillating, the light diagram will be a straight line of light. If the galvanometer reflector is oscillating the beam reflected will be at an angle to the beam which was reflected from 20 the non-oscillating reflector. When the reflector E is oscillating and the mirror G is rotating, the combined effect of the two movements will be a 25 curve-like diagram, and the amplitude of the departures from the straight line will be a measure of the amplitude of the oscillations of the galvanometer reflector. These oscillations are to be produced by variations in the characteristics of the subject of the investigation through the use of suitable mechanism influenced by such 30 variations to produce variable electric currents, which currents are to be passed through the galvanometer coil carrying the mirror, the galvanometer coil being located in the field of the usual permanent magnet. For example, an 35 engine indicator of a known kind and of the type illustrated for example in the patent to Peters, is subjected to the varying pressures within an engine cylinder in which a piston is reciprocating. These varying pressures produce variable 40 electric currents in the circuit of the engine indicator, which varying currents when passed through the galvanometer coil cause the coil and its reflector to oscillate, the amplitude of the 45 oscillations being a measure of the pressure variations and being readable by the varying amplitudes of the visible light curve.

It will be understood that the above is illustrative of but one use of the instrument constituting the subject of this invention. The details of improvement have been designed, however, more particularly for use of the instrument with engine indicators and have been found to be particularly advantageous when so used.

The disclosure of Fig. 1 is merely diagrammatic,

and since the several parts therein designated by reference letters need not necessarily take the particular form adopted in the instrument as more specifically illustrated in the other figures, these reference letters are not used on the other figures to designate the parts corresponding in a general way to the parts given reference letters in Fig. 1.

Coming now to the description of the instrument in its specific form and as illustrated in Figs. 2 to 9 inclusive, numeral 11 designates the base of a rectangular box-like structure having end panels 13 and 15 and side panels 17 and 19. A top panel 21 completes the closure. One end of the base 11 is formed with an upstanding wall 23. This wall 23 is of generally U-shaped outline when looked at from above as shown in Fig. 3. The bottom portion of the base of the U-shaped wall extends from the middle of the end of the base 11 part way to each side edge, whence the wall continues longitudinally for a short distance toward the other end of the base 11 which has a slightly elevated platform or boss 25. The end panel 15 is secured to the base 11 and to its wall 23 by screws 27. Aligned openings 29 and 31 are seen in the end panel and wall, which openings are for the passage of a light beam from a source of light. The fastening means 27 also secure a lamp bracket 33 to the panel 15. The lamp bracket has a circular opening to receive a convex lens 35 secured in position in a suitable retainer 37. At 39 is a lamp bracket extension secured to the lamp bracket by fasteners 41. Within a recess of the extension is a lens shield 43 preferably of plate glass. The extension has an external spherical surface 45 engaging a corresponding internal surface formed on a divided double lamp bracket ball socket 47. A lamp bracket ball 49 is tightly fitted to the lamp housing 51 carrying a conventional source of light, preferably an arc light. Suitable fastening means 53 are used to clamp the parts of the ball socket 47 upon the ball of the lamp housing and upon the spherical part 45 of the bracket. By the adjustment of the lamp housing relative to the socket 47 the position of the arc may be changed at will, and by the adjustment of 47 together with the lamp housing relative to the extension 39 the beam from the source of light through the center of ball 49 may be brought into alignment with the principal focus of lens 35. There is thus provided a conveniently adjustable means for positioning the light source relative to the instrument.

The light from the source after passing through the lens 35 then passes through openings 29 and 31 in the end panel and the wall 23. After passing these openings the light then is transmitted through an adjustable shutter to be described below, the shutter being located between the side members of the U-shaped wall 23. A generally horizontally positioned light shield 55 is mounted on the top edge of the U-shaped wall adjacent the end panel 15. This shield is then curved downwardly between the side members of the wall and, adjacent its other end, it is secured to posts or projections 59. A slot 57 is cut in the shield as shown in Fig. 2 for the passage of the light beam from the shutter. The purpose of this shield is to prevent any reflected rays reaching the region of the revolving mirror which is located above the shutter. To the rear of the horizontal shield is a vertical light shield 58. This shield has a vertical slot 59 for the passage of the light beam from the shutter, and it also

has a horizontally elongated slot 62 above the slot 59. This wall shuts off from the region of the galvanometer all light except a beam which is transmitted through the shutter. The horizontal slot is for the passage of the beam of light from the oscillating reflector of the galvanometer.

The top panel 21 is formed in parts, one part being in the form of a door 61 hinged as at 63 to the box. In its closed position this door engages a cross bar 65. In a depressed part of the door is a lifting ring 67. The door may be maintained in open position by links 69 and 71 hinged to the door and the box, and also to each other and operably related to hold the door in open position in an obvious manner.

Slidable along the top panel 21 and over the door 61 is a film box base 73 having an opening 75 to register with a top panel opening 77 in one position of the film box base. Over the opening 75 is an arcuate viewing screen 79. To the rear of opening 75 is the film box 81. It will be understood that the base 73 has a second opening corresponding with opening 75 and located underneath the film box 81. A slide 83 is used to cover the film within the film box in a well known manner. When the part 73 is moved to the left from its position in Fig. 2 so that the box 81 is over the opening 77, the slide 83 may be removed and the film within the box exposed to the reflected light beam just as in the case of the viewing screen as shown in Fig. 2. The correct position of the film box may be known by the position of the spring-pressed detent 85 as shown in Fig. 4. The film within the box should be arranged to travel over an arcuate surface corresponding to that of the viewing screen 79, which film may be wound on suitable spindles 87 and 89 by the use of an operating handle not shown. Access to the film is had by a removable cover 91. No novelty is herein claimed for the film box per se nor for the means for rolling the film on its spindles. For this reason no more complete showing is made of the details relating to the film box.

Each of the side members of the wall 23 is apertured to receive a bushing-supporting ring 93, these rings being secured to the aforesaid side members of wall 23 by fastening means 95. The rings 93 carry bushings 97 for the rotatable support of a mirror shaft 99. Retainer 101 is used to hold the shaft in position. Outside the panel 17 a universal joint 103 of any preferred kind may be used to connect the mirror shaft 99 to a shaft 105 which projects in alignment with shaft 99 from a gear housing 107. If it be desired to mount this gear housing rigidly with the instrument, a bracket 109 may be used to support the gear housing which bracket may be attached to the instrument by suitable fastening means. Also extending into the gear housing is a shaft 111 as shown in Fig. 3. This shaft is to be rotated by a suitable connection with the driven shaft of the engine, the characteristics of which are to be investigated. Any desired gear ratio may be secured by the provision of a suitable gear train within the gear housing 107. It has been deemed unnecessary to illustrate the gearing within the housing since no claim is being made for the specific gearing per se. Between the side members of the U-shaped wall 23 the shaft 99 is shaped to support a plurality of flat mirrors 113. The number of mirrors may be as desired, the drawings showing six of said mirrors, this being a preferred form.

As to the galvanometer per se, no novelty is being claimed. As explained above when the

oscillograph is used with an engine indicator the fluctuating current from the indicator is conducted through the loop of wire located in the field of the galvanometer magnet, and this loop carries the oscillating reflector. When the current passes through the loop of wire it is made to deflect by its reaction with the permanent magnet. This causes a rotation of the reflector. The natural frequency of this galvanometer element is high enough so that very rapid current fluctuations cause corresponding oscillating movements of the reflector.

From the above description it will be understood that a beam of light from the source passing through the shutter is reflected by the galvanometer reflector to the revolving mirror which, as it revolves, causes a line of light to be described on the screen or film. This line will be a straight line as long as the galvanometer reflector does not oscillate. If, however, there are current fluctuations in the galvanometer coil, the coil oscillates as explained above and the direction of the reflected beam is changed. On the screen the longitudinal path of the beam produced by the revolving mirror and the transverse path produced by the oscillating reflector combine to produce a curve. In this curve the amplitude of the departures from the longitudinal line serve to measure the amplitude of the oscillating movements of the reflector and therefore of the magnitude of the causes producing such oscillating movements.

It is desirable to know the condition of the galvanometer current and of the magnitude of the characteristics producing such current at predetermined positions of the moving parts of the subject under investigation. Specifically it may be desirable when making a light diagram of cylinder pressures to know the pressure at the upper and lower dead centers of the piston in its movement of reciprocation. To that end there is used a U-shaped member 115 pivoted on its two sides to and within the rings 93. This construction is illustrated in Fig. 3. The sides of the U-shaped member 115 extend up from the shaft 99 toward the viewing screen, and a wire 117 is connected to the extremities of the sides. A curved rack 118 on one side of the U-shaped member is in engagement with a pinion 121 on a pinion shaft 123 (see Fig. 2 and Fig. 7) rotatable in one side member of the U-shaped wall 23. Rotation of pinion shaft 123 operates to swing the U-shaped member 115 about its pivot and with it the wire 117. This rotation is effected by an adjusting shaft 125 shown in Fig. 3, which shaft is rotatably mounted in panel 19. The adjacent ends of shafts 125 and 123 have removable interlocking parts to facilitate the assembly and removal of the panel 19. With the shutter in its open position and with the piston in its position of upper dead center the shafts 125 and 123 may be rotated by means of a suitable handle 127 on shaft 125 until the wire 117 intercepts the light beam, cutting off the light from the viewing screen. When, thereafter, the engine is being tested and the curved light diagram is being examined, the wire 117 will cut off the light beam and make a break in the curve at the upper dead center position of the piston. To similarly shadow the light beam at the lower dead center position of the piston, a second U-shaped member 129 is used. This member 129 is shown in Fig. 2 and in Fig. 4. The drawings show it pivoted to member 115 at 131 and there is provided an adjustable pin and slot connection at 133 so

that the wire 135 carried by the ends of the sides of member 129 may be variably located in predetermined positions. This position may be that corresponding to the lower dead center position of the piston as explained above.

The light beam reflected from the oscillating reflector of the galvanometer is caused to pass through a cylindrical lens 137 on its path to the rotating mirror. This lens 137 is elongated as best shown in Fig. 7 to accommodate the variations in direction of the reflected beam resulting from the oscillations of the reflector of the galvanometer. The lens 137 is supported by a carrier 138 and posts 141, the latter supported in the upper parts of the side members of the U-shaped wall 23. As will be seen from the drawings, these posts are positioned to locate the plane of the cylindrical lens at right angles to the plane defined by the several lines corresponding to the beams of light reflected from the oscillating reflector in its several positions of oscillation.

For the purpose of determining the point in the light diagram corresponding to the instant of ignition, resort is had to the expedient shown diagrammatically in Fig. 9. A small transformer is used to superimpose an induced current on the current through the galvanometer coil at the instant of ignition, and this superimposed current gives evidence of itself by producing a slight change in the angular position of the reflector, and consequently a slight change in the direction of the reflected beam. This is but momentary, but the curve on the light diagram is given a resulting irregularity or kick corresponding to the instant of ignition. To produce this effect the primary winding of a small transformer is included in the circuit through the battery, breaker, and ignition coil associated with the engine, and the secondary winding of the small transformer is in series with the engine indicator circuit which passes through the oscillograph element, that is through the galvanometer coil carrying the reflector. The number of turns in the windings is kept small enough to avoid interfering with the operation of the oscillograph. This is fully and clearly illustrated by Fig. 9. When the ignition breaker contact points open, a small induced current irregularity is registered on the light diagram.

The shutter is mounted on the base 11 beneath the shield 55. The shutter itself is a brass cylindrical member 143. It has a diametrically located slit 145 for the passage of light. From the ends of the shutter extend axially pivots 147. The upper pivot seats rotatably in the recessed lower end of a screw 149. This screw is threaded into an upwardly directed and overhanging member 150 carried by a shutter bracket 153. The lower pivot 147 seats in a similar recess in the end of a base pivot member 151. The base pivot member 151 is threaded into the shutter bracket 153, which rotates about a boss 155 formed on the base 11 as shown in Figs. 4 and 5. The base pivot member 151 extends beyond the bracket downwardly through the base 11 within which it is rotatable. A spring 156 surrounds the extension of the base pivot member 151, and engages the base 11 and a head 157 secured to the extreme end of the base pivot member 151. In this way the bracket 153 with the parts carried thereby has a rotatable mounting relative to the base 11 but is resiliently restrained from rotation by the action of the spring whereby frictional contact is maintained between the boss and the bracket. For rotating bracket 153 one portion

thereof is provided with vertically spaced tongues 161. Between the tongues is a trunion nut 163 in threaded engagement with a shutter adjusting screw 165, the latter rotated by a shutter adjusting shaft 167, there being an interlocking engagement between the shafts 165 and 167 as between the shafts 123 and 125 and for the same purpose.

An external hand grip 169 on shaft 167 is provided. A spring 171 is used as shown in Fig. 3 to hold the screw 165 in any position to which it may have been adjusted, and a spring 172 maintains the two shafts in interlocked relation. By the adjustment described the bracket 153 is rotated and with it the shutter whereby more or less of the width of the shutter slot is rendered available for the passage of the light beam. Rotatable about a plane surfaced region of the upper screw member 149 is an arm or lever 173. In addition to the opening in 173, by which it is permitted to pivot freely on part 149, it has a second opening for the passage of the bent over end of a shutter opening rod 175, the latter removably connected to a manually operable shutter-adjusting shaft 177 extending to the outside of panel 19. The bent over end of rod 175 is so related to the shutter that when the rod 175 is pulled outwardly the shutter is rotated to locate the slot in its open position for the passage of the light beam as will be more fully explained below.

The shutter bracket 153 carries also a support 179 for an electromagnet 181. The shutter 143 has secured thereto a soft iron keeper 183. The position of the electromagnet and the keeper relative to the shutter is such that when the electromagnet is energized and the keeper is drawn toward it, the slit of the shutter is in its open position, that is in the path of the light beam from the source. As explained, the degree of opening is governed by the adjustment effected by shaft 165. To oppositely rotate the shutter to its inoperative or closed position where the slit is positioned across the path of the light beam, there is a spring 185 attached to a lug 187 on the bracket 153 and to the combined keeper and shutter. It will therefore be seen that the spring normally holds the shutter in closed position, and that the electromagnet when energized opens the shutter against the tension of the spring. The shutter may also be opened manually by the use of the rod 175 as stated above. The angular surface on the combined shutter and keeper resulting from the connection of the keeper to the shutter, forms an abutting surface which is engaged by the bent end of the rod, so that when the rod 175 is pulled this bent end engages the combined keeper and shutter and rotates the same to its open position, just as it is rotated to open position by the electromagnet. The shutter may therefore be held in open position as long as desired.

When photographing the light beam it may be desired to impress upon the film a single diagram, that is a diagram from a single one of the several surfaces of the rotating mirror, rather than to impress upon the film a series of superimposed impressions. To that end the electromagnet is used to automatically open the shutter only long enough for a single impression and to thereafter permit the shutter to close under the influence of the spring 185. The automatic means is controlled by the rotation of the mirror itself as will be now explained.

To the end of shaft 99 is secured a shutter commutator or what may be called a cam 189. This

cam is of insulating material and in the form of a threaded member 189. The cam has a contact wire located within its spiral surface and designated by numeral 191. This wire may be made to contact with shaft 99, and it is to be engaged by a contact point on an arm 193, which arm contact point and wire are, while engaged, to close a circuit and energize the electromagnet. The circuit is not illustrated as it involves no patentable novelty. It requires merely a suitable electrical connection between the wire and the electromagnet, and also an electrical connection between the arm 193 and the electromagnet, one of such connections including a source of electric current. The arm 193 is connected to one end of a shutter switch contact shaft 195. A shutter switch base 197 is secured to panel 19 and is formed with lugs as shown in Fig. 2 for the guidance axially and rotatably of said shaft 195. Slidable through end panel 15 is a push rod 198 which is intended to engage and reciprocate shaft 195. Inward reciprocation of shaft 195 under the influence of a push from rod 198 moves the arm 193 bodily from the commutator or cam 189. Pivoted to the shutter switch base 197 at 199 is a detent 201. The detent has an inclined end face 203 and a notch 205. Shaft 195 has secured thereto a pawl 207 which is intended to engage in the notch 205. A shutter switch tension spring 209 is connected to a post 202 on the detent 201, and to a second post 204 on the hub of the lever arm 193. This spring is so positioned that it becomes tensioned by the rotation of shaft 195 as influenced by the action of the screw cam 189 upon the lower end of the arm 193 as the mirror shaft rotates. When the cam 189 has rotated sufficiently to carry the contact point of the arm 193 to that end (the left end in Fig. 4) of the cam screw remote from the end at which it started, which may be referred to as the first end, the rod 198 may be operated to push the shaft 195 and with it the arm 193 bodily so that the contact point of arm 193 leaves the threaded surface of the cam. At the same time the tension in spring 209 which was produced by the action of the cam in rotating shaft 195 operates to reversely rotate shaft 195 and to restore the end of arm 193 to a position over the above-mentioned first end of the cam. The arm 193 is held in this "off" position by the engagement of the pawl 207 in the notch 205. During a part of the movement of the arm contact point along the screw cam it is in engagement with the contact wire carried by the cam. During that period of engagement the circuit through the electromagnet is closed and the shutter is opened and the exposure is made. As soon as the two contact points on the lever and cam separate, the electromagnet is no longer energized and the spring 185 closes the shutter.

For the next exposure provision is made to trip the detent 201 and release the pawl which is holding the arm contact point off the cam. For that purpose a trip shaft 219 is guided in other lugs of the switch base 197 and a spring 211 holds the trip shaft 219 in its outward position toward the panel 15. The trip shaft 219 has a cone-shaped end 213 which is intended to engage the inclined face 203 of the detent. A push rod 215 is slidable through the end panel 15 and is manually operable to push the shaft 219 against its spring 211 to cause the cone 213 to engage and lift the detent 201 from the pawl 207, whereupon the spring 209 moves the contact arm 193 into contact with the cam 189 at the said first end of

the latter. As the shaft 98 rotates, the cam then rotates the arm and the contacting points may engage and produce another exposure through the energizing of the electromagnet as explained above. It will be understood that before this second exposure a new section of film will be rotated into position unless it should be desired to superimpose one light diagram upon another. When it is desired to observe the phenomena either for the sole purpose of observation or preliminary to making a photograph, it is only necessary to lock the contact mechanism out of operation by pushing the rod 198 and permitting the detent and pawl to cooperate in holding the contact arm 193 out of engagement with the cam. With the observing screen 79 in position the rod 177 may then be pulled out to open the shutter and the light diagrams may be observed on the screen.

With an oscillograph as described and used with an engine indicator the said oscillograph panels may serve as the bases for the mounting of the engine indicator Wheatstone bridge and related accessory instruments such as a meter, resistance coils, and switches.

Among the more important advantages which result from the improved instrument are:

1. The mounting of the source of light for convenient adjustment relative to the instrument.
2. The positive driving of the rotating mirror by the engine. The mirror shaft may be directly connected to the engine shaft or it may be connected by a gear box as shown in the drawings. The gear box may be mounted on a side panel as shown in the drawings or if it be desired to avoid communicating vibrations to the instrument, it may be separately mounted.

3. The operating mechanism including the electromagnetic shutter affords an automatic arrangement for making a single or a plurality of exposures.

4. The combined film holder and viewing screen afford a ready means to convert the instrument from a photographing device to one giving a visible picture.

5. The mechanical means for checking the condition of the light curve at upper and lower dead centers constitute an especially useful feature in an instrument of this kind.

6. The expedient for determining on the curve a

point corresponding to the ignition is another valuable addition to instruments of this kind.

We claim:

1. In an oscillograph, a rotating mirror, a surface upon which a light diagram is made by light reflected from said mirror, shadow-forming means to intercept the light beam between the mirror and the surface, and means to secure said light-intercepting means in predetermined positions corresponding to positions of parts of the mechanism being investigated. 5

2. In an oscillograph, a rotating mirror, a surface upon which a light diagram is made by light reflected from said mirror, means to intercept the light beam between the mirror and the surface, 15 and means to secure said light-intercepting means in predetermined positions corresponding to positions of parts of the mechanism being investigated, said means having radial arms and a wire or the like connected to said arms to intercept the light 20 beam.

3. In an oscillograph, a rotating mirror, a surface upon which a light diagram may be traced by light reflected from said mirror during its rotation, a plurality of shadow-forming means to 25 intercept the light beam, and means to secure each of said light-intercepting means in predetermined positions corresponding to positions of parts of the mechanism being investigated.

4. The invention defined by claim 3, each of said 30 light-intercepting means carrying a shadow-making wire, one of said means being rotatably adjustable about an axis of rotation at the center of curvature of the said surface, and the other of said means being adjustable about a pivot carried 35 by the first of said means.

5. In a device for use with an engine indicator associated with an internal combustion engine having an ignition coil, said device including a galvanometer provided with an oscillating reflector, a rotating mirror and a surface to receive a light diagram, a transformer having a primary winding adapted to be connected in series with the primary winding of the ignition coil used and a secondary winding constituting a part of the 40 45 circuit from the engine indicator which circuit also includes the galvanometer coil whereby the points on the light diagram corresponding with engine ignition are indicated.
